(57) **CLAIM**

The ornamental design for a bottle and mount assembly, as shown and described.

DESCRIPTION

FIG. 1 is a right, front-side perspective view of a bottle and mount assembly.

FIG. 2 is a left, rear-side perspective view thereof.

FIG. 3 is a front-side view thereof;

FIG. 4 is a rear-side view thereof.

FIG. 5 is a right-side view thereof.

FIG. 6 is a left-side view thereof.

FIG. 7 is a top plan view thereof; and,

FIG. 8 is a bottom plan view thereof.

The broken lines shown represent portions of the bottle and mount assembly that form no part of the claimed design.

1 Claim, 8 Drawing Sheets(56)
